LOOSE LEAF FASTENER

Filed April 4, 1932

UNITED STATES PATENT OFFICE

PEYTON H. BARKLEY, OF CHICAGO, ILLINOIS, ASSIGNOR TO C. L. BARKLEY & CO., OF CHICAGO, ILLINOIS, A COPARTNERSHIP CONSISTING OF PEYTON H. BARKLEY AND CHARLES L. BARKLEY

LOOSE LEAF FASTENER

Application filed April 4, 1932. Serial No. 602,999.

This invention relates to a loose-leaf fastener and concerns itself primarily with a metal strip having a plurality of tongues cut therein which normally lie in the plane of the strip and which are designed to be deflected at substantially right angles to the strip when put into use. The tongues are so spaced on the strip as to be adapted for different punchings in the loose sheet and, for this purpose, any two or three of the tongues may be deflected from the plane of the strip for such a purpose, the other tongues not in use remaining in their cut-out position in the plane of the strip.

The metal strip or fastener is adapted for use in connection with a loose-leaf folder having inwardly directed folds between which the loose sheets are inserted. The fastener is adapted to be applied to one side of the folded portion with the tongues extending through the holes and through the sheets and crimped over on the opposite side whereby the holder also becomes reinforced at its lower portion.

The invention comprises the novel structure and combination of parts hereinafter described and more particularly pointed out and defined in the appended claim.

In the accompanying drawing which illustrates a preferred form of this invention and in which similar reference numerals refer to similar features in the different views:

Figure 1 is a fragmentary interior plan view of a loose-leaf holder involving this invention.

Figure 2 is a sectional view taken upon the line II-II of Figure 1 looking in the direction of the arrow and illustrating the fastener involving this invention in combination with the folder.

Figure 3 is an enlarged fragmentary sectional view taken upon the line III-III looking in the direction of the arrow.

In connection with this invention there is illustrated in the drawing a fibrous element 1 which may be made of any suitable fibrous material and which constitutes the cover member of the binder. This fibrous member 1 is folded to provide the side leaves or cover members 1^a and 1^b and between these cover members are a pair of inwardly directed folds

2 and 3 as shown in Figure 3. The space between the folds 2 and 3 forms a channel-like recess or pocket for receiving the lower edges of loose sheets 4 or the like.

The folds 2 and 3 are provided with a plurality of spaced apertures 5. These apertures are usually spaced to fit different punchings in the loose sheets, and those apertures in the loose sheets that correspond with the apertures in the folds 2 and 3 are adapted for receiving the proper tongues on the metal fastening element which will now be described.

The loose-sheet fastener comprises a metal strip or member 6 having spaced strengthening beads or corrugations 6^a. A plurality of resilient tongues 7 and 7^a are struck from the metal strip and normally lie in the plane thereof before being put to use. In the drawing, the loose-sheet fastener 6 is illustrated as having three (3) tongues which are designated by the reference numeral 7 as in use and as extending through the folds and the sheets and crimped over the opposite side of the folds as shown in Figure 2. The tongues 7^a which are not in proper position to engage the punched apertures in the loose sheets may remain in their normal position.

It will be obvious that, in some instances, different numbers of tongues or prongs may be used. In some instances, the prongs 7^a may be used while the prongs 7 remain in their position in the plane of the metal strip. In some events, the prong 7^a may be used and the center prong 7 may be used, depending upon the punchings of the loose sheets.

In the use of this fastener, those prongs or tongues which correspond to the punchings in the loose sheets to be used are bent at right angles to the plane of the strip and inserted through one of the folds 2 or 3. The sheets are then impaled upon the prongs and the other fold is then engaged with the tongues after which the tongues may be folded over the last-mentioned fold as shown in Figure 2.

It will be appreciated that this method greatly facilitates the use of such a folder in that the sheets are more quickly and easily assembled therewith. At the same time, this metal strip, which it will be noted extends substantially the length of the folded pocket

of the binder, stiffens and reinforces the same and produces a more durable structure.

I am aware that many changes may be made and numerous details of construction 5 may be varied through a wide range without departing from the principles of this invention, and I, therefore, do not purpose limiting the patent granted hereon otherwise than necessitated by the prior art.

10 I claim as my invention:

A loose-leaf fastener for binders, consisting of an elongated metal strip having a medial

tongue and having a pair of adjacent tongues at each end portion cut therefrom and normally lying in the plane of the strip, said tongues being axially aligned and of substantially equal length, and being adapted to be 70 selectively bent to enter differently spaced openings in different sheets to clamp the sheets to the binder.

In testimony whereof I have hereunto subscribed my name at Chicago, Cook County, 75 Illinois.

PEYTON H. BARKLEY.
